JENS ORTEN BOVING, OF WESTMINSTER, LONDON, ENGLAND

HYDROPNEUMATIC LIQUID RAISING PLANT

Application filed November 28, 1928, Serial No. 322,332, and in Great Britain November 30, 1927.

This invention relates to hydro-pneumatic liquid raising plants of the kind in which aerated liquid is raised by being drawn up the longer leg of a siphon by means of a partial vacuum maintained in and de-aerating the liquid in a closed chamber at the head of the siphon, the de-aerated liquid descending the shorter leg of the siphon, and the partial vacuum being maintained by aspiration by and 10 aeration of a column of water descending the longer leg of another siphon.

The invention also involves the use of a hydraulic air compressor and compressed air liquid raising plant of the kind in which a 15 column of water descending under a head due to difference of levels, conveys air to a chamber wherein the air becomes separated from the water and subjected to the pressure head of the water ascending to the lower of the 20 levels, and such compressed air is forced into the lower end of and raises a column of water. As however in the present invention a closed cycle is employed, a gas other than air may be used.

25 The object of the invention is to supplement the action of a vacuum liquid raising plant of the above described kind so that in one stage the liquid can be raised to a considerably higher level than by the vacuum-induced lift alone.

For this purpose, according to the invention, the height of the discharge above the liquid level at the intake of a vacuum-operated aerated liquid-raising siphon of the above described type is arranged to be greater than that to which the vacuum alone can raise the aerated liquid and the lower portion of the lift of the aerated liquid is effected by the introduction into the liquid of air or other gas under pressure, derived from a gas-separating chamber to which the descending column of aerated water in the vacuum-inducing siphon descends beneath the lower 40 level of the operative fall thereof.

45 In other words, the vacuum gas lift is assisted by a pressure gas lift, and the compressed gas for operating such gas lift is obtained by prolonging the descending leg of 50 the vacuum-generating siphon to form the

downwardly directed shaft of a hydraulic gas compressor of the above described type.

Whereas the vacuum-generating and gas-compressing portion of the system and the pressure gas and vacuum gas lift portion 55 thereof deal with different quantities and may even deal with different sources of liquid, the same gas circulates in common in the two portions of the system. As, however, there may be incomplete separation of gas and liquid 60 in the vacuum chamber at the head of the vacuum lift and also in the separator at the bottom of the compressor shaft, and as some of the gas will be absorbed by the liquid, it will be necessary to supply a certain amount 65 of fresh gas to the system. Such fresh gas can be admitted either to the vacuum chamber or, and preferably, drawn into the ascending leg of the pressure gas and vacuum 70 gas lift at a point where the pressure therein is only slightly below atmospheric pressure. This additional gas will assist the action of the pressure gas and vacuum gas lift.

A representative embodiment of a liquid 75 raising plant according to the invention is illustrated diagrammatically in sectional elevation on the accompanying drawing, in which:—

a is the upper water level on one side of a fall and *b* is the lower water level at the 80 other side thereof.

c is the shorter leg of a siphon which the water ascends to descend the the longer leg *d* which is extended by a downwardly directed shaft *e* to beneath the lower level *b*, 85 to which level *b* the water ascends by an upwardly directed shaft *f*.

g are a series of nozzles drawing in air located at the top of the longer siphon leg *d* by means of which air is drawn into the 90 water descending such leg *d* and the downwardly directed shaft *e*. The air thus drawn in is compressed at the bottom of the shaft *e* to a pressure equal to the head of water in the upwardly directed shaft *f*.

h is a chamber at the bottom of the shafts *e* and *f* and in which the compressed air separates from the water.

i is the longer leg of a vacuum water-raising siphon dipping into the water at the 100

upper level *a*. *j* is the shorter delivery leg of such siphon. *k* is a chamber at the head of the water-raising siphon *i j*, in which chamber *k* a partial vacuum is maintained by such chamber being connected by a pipe *l* to the above mentioned nozzles *g* in the descending leg *d* of the siphon *c d*.

Compressed air from the air-separating chamber *h* is supplied through a pipe *m*, controlled by a cock *n*, to air-injecting nozzles *o* which inject the air into the lower end of the leg *i* of the water-raising siphon, whereby the water therein is aerated and driven upwards by the expanding air to above the level *a*. From the height at which the air has expanded to atmospheric pressure, the water is raised by the suction exerted by the partial vacuum in the chamber *k*; wherein the expanded air separates from the water, to become drawn in by the nozzles *g* in the vacuum-inducing siphon *c d*.

The water freed from air descends the leg *j* of the water-raising siphon and discharges at level *p* considerably above the level *a* from which it was raised.

g are nozzles on the ascending longer leg *i* of the water-raising siphon at the level where the pressure is slightly below atmospheric pressure, whereby air is drawn from the atmosphere to make up for air carried away in solution or suspension in the water.

r are valve-controlled intercommunication priming passages for starting the vacuum-inducing siphon *c d* in the well known manner.

One of the main losses in efficiency in separate hydro-pneumatic plants of the types described arises in the entraining or forcing in of the air into the water. Consequently by the above described arrangement, in addition to the considerably increased height to which the liquid is lifted, the efficiency of the entire plant is considerably increased owing to the gas inlet *q* for the vacuum generator serving conjointly for the compressor, and the gas injector *o* for the pressure gas lift serving conjointly as the aerator for the vacuum gas lift, ignoring the small supplementary inlet of gas if admitted to the ascending leg of the latter, as at *q*.

There are other advantages to be derived from the above described combination as compared with either a plant consisting of a siphon vacuum generator and a vacuum air lift, or a hydraulic air compressor of the type described and a pressure air lift. The lift obtainable with a vacuum air lift is obviously limited by the practical possible vacuum obtainable, whilst although with such a hydraulic air compressor the pressure and lift can be increased by deeper excavation into the ground, deep excavations are expensive and in water-logged areas may be impossible. By the combination of both types of plant, moderately high lifts can be

attained in one stage at comparatively low cost.

With a vacuum generating siphon used alone the efficiency decreases considerably if the water level at the bottom of the longer downwardly directed leg rises to increase the submergence of the outlet thereof, as the air prior to escaping becomes compressed by the head due to the depth of submergence. Likewise when the water level at the inlet of a hydraulic compressor of the described type used alone rises, the efficiency diminishes unless by cumbersome float or hand controlled mechanism the inlet is correspondingly raised. Now, as any variation in the upper level of a fall is generally accompanied by a similar variation in the lower level, with the combined vacuum generator and compressor and pressure gas and vacuum gas lift, any reduction or increase in the vacuum due to alteration of levels will generally be accompanied by a corresponding inverse increase or reduction in the degree of compression, so that variation of the vacuum gas lift is compensated by inverse variation of the pressure gas lift and no loss of efficiency results. Moreover as the gas intake of the compressor is at the constant level in the vacuum chamber at the head of the siphon, the inlet of the compressor is independent of changes in the upper level.

As usual the ascending leg *i* of the vacuum gas lift is carried to a greater height within the vacuum chamber than the descending or delivery leg *j* thereof. Also the introduction of compressed air into the ascending leg *i* is effected at a level sufficiently beneath the lower level *a* from which the liquid is raised, for the pressure due to the head of liquid to be but slightly less than the pressure of the introduced compressed gas, so as to avoid loss of energy by excessive initial expansion of the gas, and to enable the aerated liquid to rise to the maximum height by the action of the pressure gas lift, from whence it is raised by the vacuum gas lift.

I claim:

1. In a hydro-pneumatic liquid-raising plant, a vacuum-operated liquid-raising siphon having a discharge end located above the liquid level at the intake end at a height greater than that to which the vacuum in said liquid-raising siphon alone can raise said liquid, a vacuum-inducing siphon having a limb descending to beneath the lower level of the operative fall of said vacuum-inducing siphon, means for drawing gas into said vacuum-inducing siphon connected to the crown of said liquid-raising siphon, a gas-separating chamber at the lower end of said descending limb of said vacuum-inducing siphon, an upwardly directed shaft ascending from said separating chamber to the lower level of the operative fall of said vacuum-inducing siphon, and gas-injecting means in the lower

end of the ascending limb of said liquid-raising siphon connected to said gas-separating chamber.

2. In a hydro-pneumatic liquid-raising plant, a vacuum-operated liquid-raising siphon having a discharge end located above the liquid level at the intake end at a height greater than that to which the vacuum in said liquid-raising siphon alone can raise said liquid, a vacuum-inducing siphon having a limb descending to beneath the lower level of the operative fall of said vacuum-inducing siphon, means for drawing gas into said vacuum-inducing siphon connected to the crown of said liquid-raising siphon, a gas-separating chamber at the lower end of said descending limb of said vacuum-inducing siphon, an upwardly directed shaft ascending from said separating chamber to the lower level of the operative fall of said vacuum-inducing siphon, gas-injecting means in the lower end of the ascending limb of said liquid-raising siphon connected to said gas-separating chamber, and means for drawing gas into the ascending limb of said liquid-raising siphon where the pressure therein is only slightly below atmospheric pressure.

In testimony whereof I have signed my name to this specification.
